UNITED STATES PATENT OFFICE.

ROGER S. HENDERSON AND AMOS SANDERS, OF PHILADELPHIA, PA.

BALANCE DOOR-HANGER.

SPECIFICATION forming part of Letters Patent No. 279,442, dated June 12, 1883.

Application filed May 8, 1882. (No model.)

To all whom it may concern:

Be it known that we, ROGER S. HENDERSON and AMOS SANDERS, citizens of the United States, residing in Philadelphia, Pennsylvania, have invented certain Improvements in Balanced Door-Hangers, of which the following is a specification.

Our invention relates to an improvement in that class of hangers for sliding doors in which the door is carried by a pair of levers forming a parallel-movement device, the object of our invention being to provide for the ready connection of the hanger to or disconnection of the same from the door, so that the device can be tested and its accuracy insured before applying the door thereto.

In the accompanying drawings, Figure 1 is a side view of a door and door-frame with our improved hanger, the door being open; Fig. 2, the same with the door partly closed; Fig. 3, a perspective view, showing the device employed for connecting one of the levers to the door-frame; and Fig. 4, a perspective view of the device employed for connecting the other lever to the door.

A and B are the two levers whereby the door D is hung, these levers being pivoted together in the center. The lower end of the lever A is pivoted to a plate, a, which is secured to the door-frame near the floor, the upper end of said lever carrying a roller, b, which is adapted to slide in a guide, d, secured to the rear edge of the door, near the top of the same. The lower end of the lever B is pivoted to a stud, f, on the rear edge of the door, close to the bottom, and the upper end of said lever is connected to a counterbalance-arm, F, which carries a weight, g, and is hung by radius-bars h and i to a frame, m, secured to the door-frame. As the door is moved back and forth the lower end of the lever B is caused to travel from and toward the lower end of the lever A in a horizontal line, the upper ends of the levers also approaching each other and at the same time having a vertical movement. This arrangement of levers has been heretofore used for hanging doors, and we desire to make no special claim upon it, our invention relating merely to the method of connecting the lower end of the lever B to the door and the lower end of the lever A to the door-frame. Usually the lower end of the lever A has been hung to

the door-frame by a fixed pin, and the lower end of the lever B has been connected to the door by a pin secured to a plate thereon, so that the parts had to be applied to the door before the latter was inserted into the frame, and in case any defect in the hanger was developed on trial the entire fixture had to be removed before the defect could be remedied. To overcome these objections we provide the lever B with a pin adapted to a slotted stud, f, on the door, and we hang the lower end of the lever A to an angle-plate, a, which is adapted to one of the posts of the door-frame, and is held in place by screws inserted from the outside, so that it can be readily detached when desired.

When it is desired to remove the door it is adjusted to the closed position, and the plate a is then detached from the door-frame and allowed to drop down onto the floor. This permits the lower end of the lever B to drop to the same extent, the pin of the lever being being thus removed from the slot in the stud f. The roller b is then slipped laterally from the guide d, and the door is released from the hanger.

In order to rehang the door the operations are reversed, the roller b being first slipped into the guide d, and the plate a being then elevated to its proper position and secured, the elevation of the plate causing a like elevation of the end of the lever B and the engagement of its pin with the slotted stud f.

It will thus be seen that the door can be readily applied to or removed from the hanger after the latter has been put in place in the frame, so that ample facilities are afforded for testing the hanger and getting it into proper working order before applying the door thereto.

Instead of using a slotted stud, f, on the door, a pin on the latter may be adapted to a slot in the lower end of the lever B; but the slotted stud is preferred.

We claim as our invention—

1. The combination of the door and the pivoted levers A B, forming a parallel-motion hanger therefor, the lower end of the lever B being connected by an open joint to the door, and the lower end of the lever A hung to a detachable pin at the front edge of the door-frame, as set forth.

2. The combination of the door having a slotted plate, *f*, the frame having a detachable plate, *a*, with pivot-pin, as described, and the pivoted levers A B, the former adapted at the lower end to the pivot-pin of the plate *a*, and the lever B having at the lower end a pin adapted to the slot of the plate *f*, as set forth.
- 5 3. The combination of the door and frame, the levers A B, the slotted guide *d*, the coun-

terbalance-lever F, the open joint for the lower end of the lever B, and the detachable pivot-pin for the lower end of the lever A, as set forth.

ROGER S. HENDERSON.
AMOS SANDERS.
